(57) **CLAIM**

I claim the ornamental design for a handle for beverage container, as shown and described.

DESCRIPTION

FIG. 1 is a front, left side, and top perspective view of a handle for beverage container showing my new design; FIG. 2 is a rear, left side, and top perspective view thereof; FIG. 3 is a front elevational view thereof; FIG. 4 is a rear elevational view thereof; FIG. 5 is a right elevational view thereof; FIG. 6 is a top view thereof; and FIG. 7 is a top view thereof.

FIG. 8 is an environmental front, left side, and top perspective view thereof; and,

FIG. 9 is an environmental front, left side, and top perspective view thereof.

The broken lines in the drawings depict environmental subject matter only and form no part of the claimed design.

1 Claim, 7 Drawing Sheets
